ICE CREAM CAN HOLDER FOR FREEZERS AND ICE CREAM CABINETS

Filed Aug. 23, 1928

UNITED STATES PATENT OFFICE

BESSIE M. EMIG AND WILLIAM G. DOBBS, OF AUBURN, NEW YORK

ICE-CREAM-CAN HOLDER FOR FREEZERS AND ICE-CREAM CABINETS

Application filed August 23, 1928. Serial No. 301,558.

This invention relates to an ice cream freezer structure and pertains particularly to a holder designed to hold a plurality of cans which in cross sectional design form a 5 segment of a cylinder, maintaining a number of such cans in nested relation to form a substantially cylindrical body.

The primary object of the invention is to provide, in a manner as hereinafter set forth, 10 a means for supporting a plurality of cans of the above described character in such a manner that little more space will be required than is at present required for the present cylindrical ice cream can.

15 Another object of the invention is to provide means for maintaining the cans in closely spaced relation so that a free circulation of the refrigerant therebetween will be permitted at all times to maintain the contents 20 of the cans in the proper condition of firmness.

The invention will be best understood from a consideration of the following detailed description taken in connection with 25 the accompanying drawings forming part of this specification, with the understanding, however, that the invention is not confined to any strict conformity with the showing of the drawings but may be changed or 30 modified so long as such changes or modifications mark no material departure from the salient features of the invention as expressed in the appended claims.

In the drawings:—

35 Figure 1 is a top plan view of the can holding structure embodying the present invention and showing one of the cans used therewith in position;

Figure 2 is a sectional view taken substantially upon the line 2—2 of Figure 1.

Referring to the drawing in detail wherein like numerals of reference indicate corresponding parts throughout the several views, the numeral 1 indicates a portion of a 45 cabinet provided with the structure 2 which constitutes our invention.

In order to provide means whereby a large quantity of ice cream may be stored in an ice cream cabinet in a space slightly larger 50 than the space at present employed for the

reception of a five gallon can of cream, we provide a plain or perforated cylinder 3 which is arranged in upright position in the ice or brine cabinet, which cylinder has positioned therein a plurality of perforated or plain receptacles 4 arranged in nested relation within the cylinder in the manner shown in Figure 1. The receptacles 4 are preferably of triangular cross sectional design, having two straight sides 5 and the arcuate outer wall or 60 side 6 which connects the straight sides in the manner shown.

In forming the receptacles in the substantially triangular shape described, it is possible to nest the same so that they will form a 65 substantially cylindrical body which will fit into the perforated cylinder 3.

Each of the receptacles 4 is of a size to receive an ice cream can of a substantially five gallon capacity, the cans being, of course, 70 of the same cross sectional design as the receptacles in which they are placed.

In order to permit the refrigerating medium to pass freely about each of the ice cream cans, one of which is shown in position 75 in one of the receptacles and is indicated by the numeral 7, the opposed straight faces or walls of the receptacles are maintained in slightly spaced relation to provide the channel or passage 8 therebetween. Any suitable means may be employed for maintaining 80 the receptacles in this spaced relation as for example, attaching bands or straps 9 may be used to connect the arcuate walls with the surrounding cylinder 3.

While our present description has been confined to the use of receptacles of such form that when three are placed together in nested relation, a substantially cylindrical structure results, it is, of course to be understood 90 that we do not wish to confine ourselves to such structure for it is obvious that two, four or more cans and holding receptacles may be employed to form a cylindrical structure although it is, of course, clear that if, for example, four five gallon receptacles are used, they will form a cylindrical body of some- 95 what larger size than would be formed by three five gallon receptacles.

From the foregoing description, it will 100

be seen that an ice cream cabinet provided with two openings of slightly larger size than the openings employed in the present cabinets for the reception of five gallon cream cans may be substituted for six of the present cabinet openings, three cream cans being accessible through each of the two openings.

5 While we are aware of the fact that a number of nested receptacles of triangular cross sectional design have been previously employed in various capacities, as for example, in cooking receptacles or the like, the use of a plurality of such perforated or plain receptacles held in spaced relation in an ice 10 cream cabinet cylinder, each designed to receive a similarly formed ice cream can, has not before been known or used, therefore,

15 What we claim is:—

20 1. In an ice cream freezer structure, a plurality of perforated receptacles formed to set up, when arranged in nested relation, a substantially cylindrical body, an imperforate receptacle formed to snugly fit within each of said perforated receptacles, and means 25 for maintaining said perforated receptacles in relatively closely spaced relation for permitting the free circulation of a refrigerant therebetween.

2. In an ice cream freezer structure of the 30 character described, a cylinder, a plurality of perforate receptacles of substantially triangular cross-sectional design, adapted to be nested in said cylinder to form a cylindrical compartmental body, means for maintaining 35 the adjacent faces of said triangular receptacles in spaced relation, means for maintaining said receptacles spaced from the wall of the surrounding cylinder, and an imperforate receptacle of substantially triangular cross- 40 sectional design adapted to snugly position in each of said perforated receptacles.

3. An ice cream freezer structure, comprising an outer receptacle, a perforate receptacle mounted uprightly in the first mentioned receptacle, a plurality of perforated receptacles nested in the first mentioned perforated receptacle and formed to conform to the shape thereof when so nested, means for maintaining the nested perforated receptacles 45 in spaced relation with one another and with respect to the encasing perforated receptacle, and imperforate receptacles formed to snugly position in the nested receptacles.

46 In testimony whereof we hereunto affix our 50 signatures.

BESSIE M. EMIG.
WILLIAM G. DOBBS.
